UNITED STATES PATENT OFFICE

2,446,435

OFFSET AXES MULTIPLE FRAMES OF
HANDBAGSJacob Ritter, New York, N. Y., assignor to
Minnie Ritter, New York, N. Y.

Application June 13, 1946, Serial No. 676,501

1 Claim. (Cl. 150—29)

1

This invention relates to offset axes multiple frames of handbags and has for its object to provide a movable inner bag which may be disposed in any position in the interior of the larger bag.

The invention consists in a link bar pivoted at the inner end to the pintle of a main bag and pivoted at its other end to the outer part of the pintle of a smaller bag, whereby the smaller bag pintle can be disposed in a position on an orbit of 360° in respect to the pintle of the larger bag.

The invention will be further described hereinafter, embodiments thereof shown in the drawings, and the invention will be finally pointed out in the claim.

In the accompanying drawings,

Fig. 1 is a perspective view of the improved handbag embodying the invention;

Fig. 2 is a front view partly in section of the combined frames;

Fig. 3 is an enlarged section taken on line 3—3 of Fig. 2;

Fig. 4 is a detail spaced view of the link connection;

Fig. 5 is a diagrammatic view showing the 360° orbit of the pintle of the smaller frame;

Fig. 6 is a view of a modified form of link connection, and

Fig. 7 is a view taken on section line 7—7 of Fig. 6.

Similar characters of reference indicate corresponding parts throughout the various views.

Referring to the drawings, the bag 10 has the usual frame 11, consisting of a pair of individual frame members 12 hinged at 13 and each having a closing knob 14, which when interlocked keep the frame closed. Any suitable closing device may be used. These frame members have a bag 12a attached thereto. This is known.

The improvement consists in substituting for the ordinary hinge pintle, an extended pintle 15 which extends inwardly to provide a support for a link 16 hingedly secured thereto at its inner end to enable the link 16 to make a complete revolution or pass through a path of 360°. To the free end of the link 16 there is pivoted an outwardly extending pintle 17 of a smaller bag frame 18 also consisting of the usual individual frame members 19, each having a suitable locking device thereon to enable the frame members to be held together in closed position. This smaller frame 18 is also provided with a bag, so as to form a separate small bag 19a within the larger bag 12a.

The important feature of this construction of double pivoted link 16 is that the smaller bag can be moved down into the main bag, or to

either side thereof, to enable the user to have access to the contents of the larger bag, or it may be raised for convenient access to the small bag. Preferably, the length of the link 16 is such that the smaller frame cannot be raised high enough to impede the closing of the main frame.

In the embodiment of Fig. 4, the link 16 has an upper loop 16a and a lower loop 16b. The upper loop fits over a sleeve 16c having a shoulder 16d. The upper loop 16a passes over the sleeve 16c and abuts against the shoulder 16d. The pintle 17 passes through the bore of the sleeve 16c. A sleeve 15a having a shoulder 15b engages the frames 12 and is engaged by the pintle 15, and

the pintle 15 has an enlarged spacing portion 15c, with a subcaliber extension 15d, which enters the lower loop 16b. The ends of the pintle 15 and the subcaliber portion 15d as also the ends of the pintle 17 are upset.

The modified link 26 (Fig. 6) consists of a member 27 having one end 28 bent in one direction downwardly, and the other end 29 bent in the other direction upwardly. The bent end 28 has an opening for the inner end of the pintle 30 of the main frame, and the bent end 29 has an opening for the outer end of the pintle 31 of the smaller frame. Here again the link 26 permits the movement of the pintle of the smaller bag in any position in its 360° orbit. The pintles 30 and 31 are upset at their ends.

The bag material of the smaller bag is preferably of the same kind as employed for the interior of the larger bag, the outer bag material may be leather, textile material or any other material usually employed to give an attractive appearance or merchandising value to the article.

I have described several forms of my invention, but obviously various changes may be made in the details disclosed without departing from the spirit of the invention as set out in the following claim.

I claim:

In offset axes multiple frames of handbags, having a larger pair of bagframes with fastening means and a smaller pair of bagframes with fastening means, and a pintle for each pair of bagframes, the combination of outward extensions on the pintles of the smaller bagframes, inward extensions on the pintles of the larger bagframes, and link bars each having one end pivotally connected with the inward extensions, and the other end connected with the outward extensions, said link bars spacing the pintles of the smaller frames from the pintles of the larger frames a radius distance of a circle of which

the pintles of the larger frames are the centers, whereby the pintles of the smaller bag-frames are movable in orbits of 360° with the pintles of the larger bagframes as axes to said orbits, and the smaller bagframes may be moved within the larger bagframes to any position upward or downward or laterally of the larger bag-frames by a rotative movement of the link bars.

JACOB RITTER.
